ATTORNEY.

UNITED STATES PATENT OFFICE

2,436,315

DOOR MAT WITH SCRAPER AND
REMOVABLE BRUSH

Gustavo Del Peschio Liberatore, New York, N. Y.

Application January 23, 1946, Serial No. 642,838

2 Claims. (Cl. 15—112)

1

This invention relates to new and useful improvements in door mats.

More particularly, the invention proposes a new and improved door mat which is characterized by a flexible mat body having on its top face a plurality of spaced parallel upwardly directed scraper ribs, water draining grooves along the sides of said ribs, and brush receiving troughs to the sides of said grooves. It is proposed to provide brushes in said troughs which have holding elements along their sides engaging complementary holding elements along the sides of the troughs. Preferably, these holding elements are in the nature of concaved sides on one of the parts engaging complementary convexed sides on the other of the parts.

The invention proposes to provide the water draining grooves with drain apertures for the water to drain down and through the flexible mat body. It is also proposed to provide bottom drain grooves along the bottom face of the flexible mat body which communicate with said drain apertures for draining away water from the bottom of the door mat.

The invention also proposes to provide the ends of the brushes with beveled portions engaging complementary beveled recesses formed in the ends of the troughs.

It is also proposed to bevel the edges of the flexible mat body and to arrange the tops of the beveled portions substantially level with the tips of the scraper ribs and the ends of the bristles of the brushes.

Another object of the invention is to provide one or more rods engaging through apertures in the flexible mat body and transversely through apertures in said brushes for releasably holding the brushes in position within the troughs.

A novel means is also proposed for releasably holding each rod or rods.

Another object of the invention is the construction of an article as described, which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a plan view of a door mat constructed in accordance with this invention.

2

Fig. 2 is a fragmentary enlarged detailed view of a portion of Fig. 1.

Fig. 3 is a fragmentary enlarged vertical sectional view taken on the line 3—3 of Fig. 1.

Fig. 4 is a fragmentary enlarged vertical sectional view taken on the line 4—4 of Fig. 1.

Fig. 5 is a fragmentary enlarged vertical sectional view taken on the line 5—5 of Fig. 1.

The door mat, in accordance with this invention, includes a flexible mat body 10 having on its top face a plurality of spaced parallel upwardly directed scraper ribs 11. Water draining grooves 12 are disposed along the sides of the ribs 11. Brush receiving troughs 14 are disposed to the sides of the grooves 12. Brushes 15 are mounted in the troughs 14 and are provided with holding elements 30 along their sides engaging complementary holding elements along the sides of the troughs 14. These holding elements 30 are in the nature of concaved sides on the brushes 15 engaged by convexed sides formed along the sides of the troughs 14, see Figs. 3 and 4.

The water draining grooves 12 are provided with a plurality of drain apertures 16 extending down through the flexible mat body 10 and connecting with bottom drain grooves 17 extending from end to end of the mat body. The ends of the brushes 15 are formed with beveled end portions 18 which engage complementary recesses 19 formed in the ends of the troughs 14. The flexible mat body 10 has beveled edge portions 20 along its sides and ends. The top edges of the beveled edge portions 20 are disposed substantially level with the tops of the scraper ribs 11 and with the tips of the bristles of the brushes 15.

One or more rods 22 are engaged through apertures 23 formed in the flexible mat body 10 and are also engaged transversely through aligning apertures 23' formed in said brushes 15. The rods 22 are associated with means by which they are releasably held in position. This means includes a head 24 formed upon one of the ends of each rod 22. The heads 24 normally engage in limiting recesses 25 formed in the top faces of bosses 26 projecting from the beveled edge portions 20. At the ends of the mat, the beveled edge portions 20 are formed with bosses 27 which are provided with finger engaging recesses 28 by which the door mat may be easily gripped and lifted.

The operation and use of the new and improved door mat may be understood from the following:

55 The door mat is placed in the usual way in

front of a door. Before entering the apartment, persons wipe their feet on the mat. The scraper ribs 11 will scrape off snow and water from the shoes, which will enter the water draining grooves 12 and drain through the drain apertures 16 and then flow along within the drain grooves 17 and in this way discharge from beneath the door mat. The bristles of the brushes 15 will assist in wiping the shoes dry and clean. The rods 22 will securely hold the ends of the brushes 15 when the mat is lifted and carried.

The flexible mat body 10 may be constructed of rubber, or other flexible materials. The brushes 15 may also be constructed of rubber, other flexible materials, or rigid materials, if this is desired. The rods 22 may be easily removed by pressing the bosses 26 downwards so as to free the heads 24 of the rods 22 from the limiting recesses 25. The rods 22 may now be pulled out. The brushes 15 are now free to be removed. The brushes 15 are held in position merely by the inter-engaging holding elements, the curved sides, along the sides of the brushes, as previously explained. They are also held in position by the beveled end portions 18. However, any brush 15 may be manually gripped and pulled out from its trough 14. In this way worn out brushes 15 may be replaced.

While I have illustrated and described the preferred embodiment of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A removable brush door mat, comprising a flexible sheet-like mat body having flexible beveled edge portions along its sides and ends, a plurality of interspersed scraper rib portions and water drain grooves to the sides of said scraper rib portions and brush receiving troughs set below the tops of said scraper rib portions and the tops of said scraper rib portions being substantially level with the tops of said beveled edge portions, said mat body also having drain apertures at points along said drain grooves and bottom drain grooves in its bottom face connected

with said drain apertures, brushes mounted in said troughs, rods engaging through apertures in said flexible mat body and transversely through apertures in said brushes, said rods being provided with heads, and bosses upon said flexible beveled edge portions beneath said heads and having limiting recesses receiving said heads, whereby when said edge portions are flexed said limiting recesses are moved clear of said heads and said rods are free to be withdrawn.

2. A removable brush door mat, comprising a flexible sheet-like mat body having flexible edge portions along its sides and brush receiving troughs, brushes mounted in said troughs, rods engaging through apertures in said flexible mat body and transversely through apertures in said brushes, and means for holding said rods from being withdrawn including limiting bosses on said flexible edge portions for engagement with the adjacent ends of said rods, whereby said flexible edge portions may be flexed to move said limiting bosses free of the ends of said rods which may then be withdrawn.

GUSTAVO DEL PESCHIO LIBERATORE.
